(57) **CLAIM**

The ornamental design for a magnetic tiles set, as shown and described.

DESCRIPTION

FIG. 1 is a perspective view of a magnetic tiles set, showing the assembly of pieces of the first embodiment for my new design;

FIG. 2 is a perspective view of the first piece thereof; FIG. 3 is a front elevational view thereof, the rear elevational view is identical;

FIG. 4 is a left side view thereof, the right side view is identical;

FIG. 5 is a top plan view thereof;

FIG. 6 is a bottom plan view thereof;

FIG. 7 is a perspective view of the second piece thereof;

FIG. 8 is a front elevational view thereof, the rear elevational view being a mirror image of FIG. 8;

FIG. 9 is a left side view thereof;

FIG. 10 is a right side view thereof;

FIG. 11 is a top plan view thereof;

FIG. 12 is a bottom plan view thereof;

FIG. 13 is a perspective view of the third piece thereof;

FIG. 14 is a front elevational view thereof, the rear elevational view is identical;

FIG. 15 is a left side view thereof, the right side view is identical;

FIG. 16 is a top plan view thereof;

FIG. 17 is a bottom plan view thereof;

FIG. 18 is a perspective view of the fourth piece thereof;

FIG. 19 is a front elevational view thereof, the rear elevational view being a mirror image of FIG. 19;

FIG. 20 is a left side view thereof, the right side view is identical;

FIG. 21 is a top plan view thereof, the bottom plan view is identical;

FIG. 22 is a perspective view of the fifth piece thereof;

FIG. 23 is a front elevational view thereof, the rear elevational view is identical;

FIG. 24 is a left side view thereof, the right side view is identical;

FIG. 25 is a top plan view thereof, the bottom plan view is identical;

FIG. 26 is a perspective view of the sixth piece thereof;

FIG. 27 is a front elevational view thereof, the rear elevational view is identical;

FIG. 28 is a left side view thereof, the right side view is identical;

FIG. 29 is a top plan view thereof, the bottom plan view is identical;

FIG. 30 is a perspective view of the seventh piece thereof;

FIG. 31 is a front elevational view thereof, the rear elevational view is identical;

FIG. 32 is a left side view thereof, the right side view is identical;

FIG. 33 is a top plan view thereof, the bottom plan view is identical;

FIG. 34 is a perspective view of the eighth piece thereof;

FIG. 35 is a front elevational view thereof, the rear elevational view is identical;

FIG. 36 is a left side view thereof, the right side view is identical;

FIG. 37 is a top plan view thereof, the bottom plan view is identical;

FIG. 38 is a perspective view of the ninth piece thereof; FIG. 39 is a front elevational view thereof, the rear elevational view is identical;

FIG. 40 is a left side view thereof, the right side view is identical;

FIG. 41 is a top plan view thereof, the bottom plan view is identical;

FIG. 42 is a perspective view of the tenth piece thereof; FIG. 43 is a front elevational view thereof, the rear elevational view is identical;

FIG. 44 is a left side view thereof, the right side view is identical;

FIG. 45 is a top plan view thereof, the bottom plan view is identical;

FIG. 46 is a perspective view of the eleventh piece thereof; FIG. 47 is a front elevational view thereof, the rear elevational view is identical;

FIG. 48 is a left side view thereof, the right side view is identical;

FIG. 49 is a top plan view thereof, the bottom plan view is identical;

FIG. 50 is a perspective view of a magnetic tiles set, showing the assembly of pieces of the second embodiment for my new design;

FIG. 51 is a perspective view of the first piece thereof; FIG. 52 is a front elevational view thereof, the rear elevational view is identical;

FIG. 53 is a left side view thereof, the right side view is identical;

FIG. 54 is a top plan view thereof;

FIG. 55 is a bottom plan view thereof;

FIG. 56 is a perspective view of the second piece thereof;

FIG. 57 is a front elevational view thereof, the rear elevational view being a mirror image of FIG. 57;

FIG. 58 is a left side view thereof;

FIG. 59 is a right side view thereof;

FIG. 60 is a top plan view thereof;

FIG. 61 is a bottom plan view thereof;

FIG. 62 is a perspective view of the third piece thereof;

FIG. 63 is a front elevational view thereof, the rear elevational view is identical;

FIG. 64 is a left side view thereof, the right side view is identical;

FIG. 65 is a top plan view thereof;

FIG. 66 is a bottom plan view thereof;

FIG. 67 is a perspective view of the fourth piece thereof;

FIG. 68 is a front elevational view thereof, the rear elevational view is identical;

FIG. 69 is a left side view thereof, the right side view is identical;

FIG. 70 is a top plan view thereof, the bottom plan view is identical;

FIG. 71 is a perspective view of the fifth piece thereof; FIG. 72 is a front elevational view thereof, the rear elevational view is identical;

FIG. 73 is a left side view thereof, the right side view is identical;

FIG. 74 is a top plan view thereof, the bottom plan view is identical;

FIG. 75 is a perspective view of the sixth piece thereof; FIG. 76 is a front elevational view thereof, the rear elevational view is identical;

FIG. 77 is a left side view thereof, the right side view is identical;

FIG. 78 is a top plan view thereof, the bottom plan view is identical;

FIG. 79 is a perspective view of the seventh piece thereof;

FIG. 80 is a front elevational view thereof, the rear elevational view is identical;

FIG. 81 is a left side view thereof, the right side view is identical;

FIG. 82 is a top plan view thereof, the bottom plan view is identical;

FIG. 83 is a perspective view of the eighth piece thereof;

FIG. 84 is a front elevational view thereof, the rear elevational view is identical;

FIG. 85 is a left side view thereof, the right side view is identical;

FIG. 86 is a top plan view thereof, the bottom plan view is identical;

FIG. 87 is a perspective view of the ninth piece thereof;

FIG. 88 is a front elevational view thereof, the rear elevational view is identical;

FIG. 89 is a left side view thereof, the right side view is identical;

FIG. 90 is a top plan view thereof, the bottom plan view is identical;

FIG. 91 is a perspective view of the tenth piece thereof;

FIG. 92 is a front elevational view thereof, the rear elevational view is identical;

FIG. 93 is a left side view thereof, the right side view is identical;

FIG. 94 is a top plan view thereof, the bottom plan view is identical;

FIG. 95 is a perspective view of the eleventh piece thereof;

FIG. 96 is a front elevational view thereof, the rear elevational view is identical;

FIG. 97 is a left side view thereof, the right side view is identical; and,

FIG. 98 is a top plan view thereof, the bottom plan view is identical.
